Unger,

UNITED STATES PATENT OFFICE.

SALOMON UNGER, OF PHILADELPHIA, PENNSYLVANIA.

SAFETY-CATCH.

1,085,884.

Specification of Letters Patent.

Patented Feb. 3, 1914.

Application filed February 6, 1913. Serial No. 746,513.

To all whom it may concern:

Be it known that I, SALOMON UNGER, a subject of the King of Austria, residing at Philadelphia, in the county of Philadelphia and State of Pennsylvania, have invented 5 certain new and useful Improvements in Safety-Catches, of which the following is a specification.

My invention relates to improvements in 10 safety catches, and more particularly to devices of this character adapted to be used in connection with breast pins, and the like, which will elastically hold the pin in the catch and prevent accidental movement.

15 A further object is to provide a device of this character in which the movable member comprises an angular pivoted guard which is provided with a spring tongue movable over a shoulder on the catch so as to hold 20 the guard in either its open or closed position.

With these and other objects in view, the invention consists in certain novel features of construction and combinations and arrangements of parts as will be more fully hereinafter described and pointed out in the claim.

In the accompanying drawings: Figure 1 is a perspective view of a breast pin illustrating 30 my improvements in connection therewith. Fig. 2 is a view in section on the line 2—2 of Fig. 4. Fig. 3 is an end elevation of the device shown in Fig. 1. Fig. 4 is a view in section on the line 4—4 of Fig. 3. Fig. 5 is a perspective view of the catch, and Fig. 6 is a perspective view of the guard.

1 represents a breast pin having a pin 2 connected thereto by a hinge 3. The pointed end of pin 2 is adapted to be positioned 40 in a catch 4, and held against accidental displacement by means of my improved guard 5.

The catch 4 comprises a shank 16 having a hook shaped pin-receiving outer end 6, 45 and at the juncture of said hook shaped outer end and the shank, the catch is formed with an integral rectangular enlargement 7 forming two flat faces 8 and 9 at right angles to each other and meeting at a relatively sharp shoulder 10. The shank 16 is 50 provided with an opening 11 for the recep-

tion of a rivet 12 to pivotally connect the guard to the catch. The guard is composed of spring metal of general U-shape in cross section with its side members preferably of 55 somewhat triangular form as indicated and having openings 13 to receive the rivet 12 when projected through the opening 11 and pivotally connect the guard in place. The guard, at its angles, is split from its lower 60 end upwardly the desired distance as indicated at 14 to form a spring tongue 15, and this spring tongue elastically bears against the flat surfaces 8 and 9 to hold the guard either in its closed or open position, and said 65 tongue is caused to move outwardly when the guard is swung to either position by reason of the shoulder 10.

When the pin 2 is to be inserted in the catch, the guard is swung down to a horizontal position with its spring tongue 15 engaging the flat surface 9. When the pin 2 is in place, an upward movement of the guard will cause the spring tongue 15 to ride over the shoulder 10, and will then elastically bear against the flat surface 8 and hold the guard in closed position. It will thus be noted that with my improvements, it will be impossible for the guard to accidentally open, but when opened, will remain 80 in such a position so as not to interfere with the entrance of the pin and the catch. These are features of importance, and as such features are embodied in a construction which is of extreme simplicity, they produce 85 vastly improved results.

Various slight changes might be made in the general form and arrangement of parts described without departing from my invention, and hence I do not limit myself to the 90 precise details set forth, but consider myself at liberty to make such changes and alterations as fairly fall within the spirit and scope of the appended claim.

Having thus described my invention, what 95 I claim as new and desire to secure by Letters Patent is:

The combination with a catch comprising a shank having a hook-shaped pin-receiving outer end, and an integral rectangular enlargement at the juncture of said shank and hook-shaped outer end forming two flat faces 100

at an angle to each other, of a guard of general channel shape pivotally connected to the shank, said guard having its intermediate portion constituting a spring tongue 5 adapted to engage both of said flat faces and elastically hold the guard in either its open or its closed position, substantially as described.

In testimony whereof I have signed my name to this specification in the presence of 10 two subscribing witnesses.

SALOMON UNGER.
